Coal Stove) - and I do hereby declare that the following is a full and exact description of the same - reference being had to the accompanying drawings and to the letters and figures of reference marked thereon - making part of this specification -

The accompanying drawing, Fig 1. represents a perspective view of the stove resting on its feet - showing its front side and top -

a. represents the door of the stove, ornamented with a small moulding around its edge, and furnished with the representation of a shell carved on it - in its center in relief - d. represents the side plate - part of which has a semi-circular form and ornamented with a shell - represented in relief similar to the one on the door. The plates around their edges - at their sides and bottoms are furnished with mouldings and ornamented with drop work, f. B. B. & C. C. are semi-elliptical projections on each side of front plate, fluted from their edges to their center as represented in the drawing - e. e. e. represent gothic drops attached to the under edge of the plate below the door.

The top plate is furnished with a flange that projects out and down - the edge of which is ornamented - by having it cut into semi-circular forms as represented in the drawings annexed - The remainder of the ornamental parts and configurations not herein described are fully represented in the accompanying drawing.

What I claim as my invention or production and desire to have secured by Letters Patent is the combination and arrangement of the ornamental forms and configurations represented in the accompanying drawings, forming an ornamental design for a stove, as described -
